STACKING MACHINE

Arthur E. Rineer, Centerville, Ohio

Application January 12, 1949, Serial No. 70,565

20 Claims. (Cl. 271—68)

This invention relates to a jogging or assembling machine or a machine for stacking signatures as they come from a printing press or from any other suitable source of supply.

As signatures are delivered by a printing press, they usually drop down without being accurately positioned. Before the signatures can be assembled and bound into a publication, it is necessary to accurately position the margins of the signatures that are to be bound. The signatures coming from a printing press are generally stacked, then placed on skids or trucks and held in storage in readiness for use in the bindery. Usually they are loosely stacked, resulting in frequent mishaps, as for example, accidentally upsetting a stack. These upset stacks result in waste material, due to damage and soiling and much additional labor to salvage whatever can be used.

An object of this invention is to assemble signatures and place them in magazines or containers in readiness for use, this being accomplished by feeding the signatures through a helical path so as to rotate the signatures through an angle of substantially 90°, to thereby position the signatures on edge. After this has been done, the signatures are aligned side by side and fed through a chute, the width of the chute preferably being less than the length of the signatures, the signatures extending transversely across the chute so that the signatures are bowed or curved when passing through the chute in readiness to be carried to a storage stack or in readiness to be automatically fed into a magazine or a container.

Other objects and advantages reside in the construction of parts, the combination thereof and the mode of operation, as will become more apparent from the following description.

In the drawings,

Figure 1 is a side elevational view of the signature assembling machine.

Figure 2 is a top schematic plan view to show the path of the signatures.

Figure 3 is a cross sectional view taken substantially on the line 3—3 of Figure 1.

Figure 4 is another cross sectional view taken substantially on the line 4—4 of Figure 1.

Figure 5 is another cross sectional view taken substantially on the line 5—5 of Figure 1.

Figure 6 is an enlarged top plan view of the chute into which the signatures are fed, together with the mechanism for delivering the signatures into the chute.

Figure 7 is a fragmentary cross sectional view taken substantially on the line 7—7 of Figure 6.

Figure 8 discloses a container or magazine mounted upon a chain conveyor.

Figure 9 is a perspective view of a truck adapted for use in transporting and storing the signatures.

Referring to the drawings, the reference character 20 indicates a leg supporting one end of the conveyor including the shaft 22, which will be described more fully later. The leg 20 is mounted upon a foot portion 24 which prevents side swaying of the conveyor. The leg 20 consists of two parts telescopically disposed, so as to permit adjustment of the height to accommodate printing presses of various heights, as will appear more fully later. A leg 26, similar to the leg 20, is also mounted upon the foot portion 24 and may be referred to as a centrally disposed leg, in that it is located near the end of the conveyor and under the packing assembly. The

2

packing assembly is supported upon a pair of legs 30, supporting the end of a rectangular frame 32.

The device supported upon the frame consists broadly of (A) a conveyor for orienting the signatures; (B) the driving mechanism; (C) a vibrating mechanism or jogging mechanism; (D) a packing mechanism and (E) a storage device. These will now be described separately.

Conveyor for orienting the signatures

10 The signatures, or folded sheets of printed material, are generally delivered from the printing press in a horizontal position. It is quite desirable to stack the signatures in piles with the folded margins accurately aligned with each other in readiness for the bindery. In the past, it has been common practice to carry a stack of signatures from the delivery platform to a skid or truck, this requiring a considerable amount of labor.

20 In the embodiment disclosed herein, as shown schematically in Figure 2, the signatures 40 are fed through a path such that the signatures eventually rest upon the folded margin 42. The conveyor for orienting the signatures from a horizontal position to a vertical position consists of a plurality of rollers 44, which may be tubular members, as best shown in Figure 3. Each roller 44 is provided with a cylindrical core 46, attached to a shaft 48 journaled in housings 50 fixedly mounted in a suitable aperture in the shaft 22. The angle of inclination of succeeding rollers 44 increases gradually, so that the rollers located to the extreme left of Figure 1 are substantially horizontally disposed and the rollers toward the other end of the carriage, as shown in Figure 1, are substantially vertically disposed. This has been accomplished by providing the shaft 22 with a plurality of apertures having the angle of inclination increased progressively from one end of the shaft to a point near the other end of the shaft.

25 The folded margins 42 of the signatures 40 contact rollers 60 arranged at right angles to adjacent rollers 44 journaled in suitable bearings and housings mounted in the shaft 22. The rollers 60 adjacent the printing press are substantially vertically disposed, whereas the rollers 60 adjacent the other end of the conveyor are substantially horizontally disposed. The rollers 60 are spaced further apart than the rollers 44, in that the signatures have greater rigidity in the plane of the signatures, as compared to a direction normal to the plane of the signatures. The rollers 44 and the rollers 60 are driven from a suitable electric motor 62.

Driving mechanism

30 The electric motor 62 is mounted upon a bracket 64 provided with angular adjustment by means of a brace 66. The bracket 64 is attached to the leg 26. The motor 62 drives a belt 68 driving a pulley 70 keyed to a drive shaft 72 journaled in bearings 74. The bearings 74 are mounted upon a ledge 80 pivotally attached to the leg 26 and biased downwardly by a weight 82. A belt 84, driven from a pulley 86 keyed to the shaft 72 passes over idler pulleys 88, as best seen in Figure 5, over a pulley 90 and a pulley 92, shown in Figure 1, and in contact with the pulleys 94, 96, 98 and 100. The belt 84 is tensioned by a weight 85 suspended from an idler pulley 87. The pulleys 90, 92, 94, 96, 98 and 100 are each keyed to the end of its shaft 48. By this arrangement the belt 84 drives some of the rollers 44. The rollers 44 located between the rollers driven by the belt 84 are driven by means of belts 102, passing over pulleys 104 keyed to the shafts 48.

35 The rollers 60, arranged at right angles to the rollers 44, are also driven by the belt 84 passing over the pulleys 110 keyed to shafts extending through the shaft 22 and fixedly attached to the tubular rollers 60. Belts 112, passing over pulleys 114, drive the rollers 60 rotating between the rollers that are driven by the pulleys 110.

40 In order to start the signatures being fed over the rollers 44, an idler roller 120 mounted on a lever 122 fulcrumed at 124, exerts a downward pressure upon the signatures, so as to press them into contact with the rollers 44 to pull the signatures from the fixed support of the printing press. The pressure of the roller 120

may be adjusted by a weight 126 adjustably mounted upon the lever 122.

Furthermore, in order to cause the signatures as they pass over the rollers 44 to contact there rollers, a plurality of floating members 130, rotatably mounted upon standards 132 and held in a floating position by springs 134, normally rest in close proximity to the rollers 44, as shown in Figure 4. The lower ends of members 130 are provided with rubber rollers 136, having rolling contact with the signatures. The floating members 130 insure uniform movement of the signatures.

In view of the fact that the folded margins of the signatures should all lie in a common plane, it is necessary to urge the signatures towards the rollers 60, so that the folded margins roll in contact with these rollers. In most cases the weight of the signatures will cause the signatures to contact the rollers 60; but occasionally a signature may stick and thereby be prevented from dropping into contact with the rollers 60.

A plurality of eccentric jogging members 140, terminating in flanged discs 142, are keyed to shafts 144 journalled in bearings 146, each jogging member being driven by a pulley 148 driven by a belt 150 actuated by a pulley 152 secured to the end of a selected roller 60. As best seen in Figure 4, there are four of these jogging members 140 and due to the eccentricity of members 140, it can be readily seen that as these members 140 rotate, they will intermittently engage the edges of the signatures opposite the folded edges, thereby urging the signatures into contact with the rollers 60. Each of the jogging members 140 is provided with saw-tooth-like marginal grooves 147, preventing the signatures from slipping or curling under members 140 when coming into contact therewith.

Vibrating mechanism or jogging mechanism

The signatures pass from the conveyor into a vibrating mechanism. In order to aid the rollers to push the signatures on to the vibrating mechanism, the signatures pass between a pair of boosters 160. Each of these boosters is mounted upon a shaft 164, slidably mounted in an oscillatory support 166. The end of each shaft 164 is attached to a cam follower 168 mounted upon an eccentric cam 170 driven by a shaft 172 having fixedly attached thereto a bevelled gear 174 meshing with a bevelled gear 176 keyed to a shaft 180 driven by a pulley 182 actuated by a belt 184 passing over a pulley 186 keyed to the drive shaft 72. This causes the booster members 160 to travel through a substantially oval path, the two boosters coming together, so as to grip the signatures, then pull the signatures from the conveyor in a vertical position past knurled rollers 190 keyed to a shaft 192 driven by a pulley 194 by means of a V-belt 196 passing over a pulley 198 keyed to a shaft 200. The shaft 200 is driven by a V-belt 202 passing over a pulley 204 keyed to a shaft 206, shown in Figure 1, driven by a belt 208 from the shaft 172.

As the signatures are advanced, they pass over a vibratory platform 210 that is vibrated electromagnetically by an electromagnet vibrator 212. This vibratory platform or support 210 is provided with a plurality of vent holes 214 overlying an air conduit 216 supplying air under pressure from a hose 218 connected to a suitable source of air pressure (not shown), so as to force air upwardly between the signatures, tending to separate the signatures on the vibratory support. However, the air pressure is insufficient to lift the signatures from the vibratory support.

Packing mechanism

As the signatures are advanced upwardly, in reality horizontally, as viewed toward the top of Figure 6, the sheets are actuated upon by a packing mechanism including a reciprocatory member 220 extending across the end of the chute 222. This reciprocatory member 220 is fixedly attached to a U-shaped bracket 224, the legs of which function as a pair of cam followers for the eccentric 226 keyed to the shaft 206. Upon rotation of the shaft 206 by the driving mechanism, as has already been described, the reciprocatory member 220 is both reciprocated and oscillated, in that one end of member 220 is attached to a bracket 230 provided with a pin 232 mounted for reciprocatory movement in a stationary slot 234. The reciprocatory member 220 has fixedly attached thereto a leaf spring 240 secured to a support 242 and extending in both directions from the support 242, one end extending over a portion of the conveyor, as has al-

ready been described, so as to guide the signatures upon the vibratory support. The other end of the spring 240 overlaps a resilient packing member 250 made from sheet metal or any other flexible material. Member 250 is attached to a cam follower 252 actuated by a cam 254, as best seen in Figure 7. The ends of member 250 are reciprocated by member 220. The center of member 250 is actuated by the cam follower 252. The cam follower 252 makes a larger stroke than does the cam actuating member 220. This results in the center portion of member 250 traveling through a greater stroke than the ends of member 250. This results in the signatures being curved, in that the center of the signatures are pushed a greater distance than the ends as the signatures are advanced into the packing compartment.

The signatures are packed into the chute 222. The sides 260 and 262 are spaced apart a distance less than the overall length of the signatures. That being the case, without folding the ends of the signatures, it is necessary for the signatures to be bowed when extending across the chute. In order to facilitate the movement of the signatures from the vibratory support 210 upon the bottom of the chute 222, the sides of the chute are provided with several sets of rollers 264, 266 and 268, belt driven, so as to actuate the ends of the signatures, the centers of the signatures being actuated more forcibly by the center of the flexible packing member 250. A magnet vibrator 249 is mounted under the chute 222, so as to vibrate the chute, to thereby facilitate the movement of the signatures through the chute.

Storage device

As the signatures are gathered in the chute 222, they are gradually advanced into a container or magazine 270 provided with side walls 272 and 274, the arcuate end 276 and the bottom 278. Side rails 280 are fixedly secured to the sides of the container 270. This chute has its forward end projecting under the end of the chute 222, as best seen in Figure 7. The container 270 rests upon the frame member 32. When the container 270 has a sufficient quantity of signatures therein, the attendant separates the signatures at the proper place, shoving the signatures to be carried away into the container, then removing the container and substituting a new container therefor.

In the embodiment shown in Figure 8, the side rails 280 are inserted into a track or guide rail 282 fixedly attached to chain conveyors 284 and 286 by means of brackets 290 and 292.

Due to the fact that it is not deemed feasible to synchronize the operation of the bindery with the printing press for various reasons, it is quite customary in the larger publishing houses to print an issue and place it in storage so that the printed signatures can be assembled in the bindery whenever the bindery is available. In this event, the containers 270 may then be stored in trucks 300 provided with a plurality of partitions 302 having guide rails 304 mounted on the partitions and upon the side walls. Thus, the containers may be stacked as shown in Figure 9. In this figure some of the containers have been indicated as being filled, while others are empty. Furthermore, some of the rails do not have any containers. This is to depict actual operating conditions, wherein the truck has empty containers ready to be filled, containers being filled and others which have been filled. The trucks 300 may be placed on elevator platforms 310 so as to bring the storage rails to a convenient level for the operator and so as to store the trucks on different levels to economize on space.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In an assembling machine for stacking signatures having a folded margin, the combination including means for receiving the signatures in a horizontal position, means for orienting the signatures into a vertical position with the folded margins at the bottom, and means for positioning the folded margins of the signatures in a common plane comprising a plurality of eccentric jogging

members adapted upon being rotated to intermittently engage the edges of the signatures opposite the folded margins so as to urge the signatures into contact with a set of aligning rollers, a pair of boosters, a vibratory platform, said boosters assisting the moving of the signatures to the vibratory platform, and means for packing the signatures into a chute.

2. In an assembling machine for stacking signatures, the combination including means for receiving the signatures in a horizontal position, means for orienting the signatures into a vertical position, and means for positioning the lower margins of the signatures in a common plane comprising a plurality of eccentric jogging members adapted upon being rotated to intermittently engage the edges of the signatures opposite the folded margins so as to urge the signatures into contact with a set of aligning rollers, a pair of boosters, a vibratory platform, said boosters assisting the moving of the signatures to the vibratory platform, and means for packing the signatures into a chute.

3. In an assembling machine for stacking signatures according to claim 2, wherein means for orienting the signatures in a vertical position consists of two sets of rollers, one set of rollers supporting one set of signatures and the other set of rollers supporting the folded margins, the angle of inclination of the first set of rollers gradually increasing from a horizontal position at the receiving end of the orienting means into a vertical position at the delivery end thereof, the other set of rollers having an angle of inclination decreasing from the vertical position at the receiving end to a substantially horizontal position at the delivery end.

4. In an assembling machine for stacking signatures according to claim 2, wherein the chute consists of a magazine the width of the magazine being less than the length of the signatures, the packing means bowing the signatures so as to cause the signatures to be stacked in arcuate formation.

5. In an assembling machine for stacking signatures according to claim 2, wherein the means for orienting the signatures into a vertical position includes a plurality of horizontal rollers of uniform diameter for receiving the signatures in a horizontal position, the angle of inclination of succeeding rollers increasing with respect to a horizontal plane so as to orient the signatures from a horizontal position to a vertical position, and wherein the eccentric jogging members consist of a plurality of concentrically disposed flanged rollers for engaging the margins of the signatures opposite the folded margins.

6. In an assembling machine for stacking signatures according to claim 2, wherein the means for orienting the signatures into a vertical position includes a plurality of horizontal rollers for receiving the signatures in a horizontal position, the angle of inclination of succeeding rollers increasing with respect to a horizontal plane so as to orient the signatures into a vertical position as the signatures are fed by the rollers, some of the rollers being shorter than the others.

7. In an assembling machine for stacking signatures having one margin to be bound, the combination including means for receiving the signatures in a horizontal position, means for orienting the signatures into a vertical position with the margins to be bound on the bottom, a vibratory support, means for feeding the oriented signatures upon said vibratory support, means for vibrating the vibratory support, said vibratory support having a plurality of apertures, means for directing air under pressure upwardly through the apertures in the vibratory support to thereby tend to separate the signatures so as to align the margins to be bound, and packing means for actuating the signatures laterally upon the vibratory support.

8. In an assembling machine for stacking signatures having one margin to be bound, the combination including means for receiving the signatures in a horizontal position, means for orienting the signatures into a vertical position with the margins to be bound on the bottom, a vibratory support, means for feeding the oriented signatures upon said vibratory support, means for vibrating the vibratory support, said vibratory support having a plurality of apertures, means for directing air under pressure upwardly through the apertures in the vibratory support to thereby tend to separate the signatures so as to align the margins to be bound, packing means for

actuating the signatures laterally upon the vibratory support, and a chute aligned with the vibratory support for receiving the signatures actuated by the packing means for accumulating the signatures in readiness for stacking.

9. In an assembling machine for stacking signatures having one margin to be bound, the combination including means for receiving the signatures in a horizontal position, means for orienting the signatures into a vertical position with the margins to be bound on the bottom, a vibratory support, means for feeding the oriented signatures upon said vibratory support, means for vibrating the vibratory support, said vibratory support having a plurality of apertures, means for directing air under pressure upwardly through the apertures in the vibratory support to thereby tend to separate the signatures so as to align the margins to be bound, packing means for actuating the signatures laterally upon the vibratory support, a container having an open end directed toward the vibratory support, and means for conveying the signatures on edge from the vibratory support to the container, said container being removably mounted so as to permit the signatures to be transported in the container.

10. In an assembling machine for aligning and stacking signatures provided with a margin to be bound, the combination including means for orienting the signatures to be stacked from a horizontal position into a vertical position with the margins to be bound on the bottom, a vibratory support, booster members for feeding the signatures longitudinally upon the vibratory support, and means for actuating the signatures laterally on the vibratory support comprising a resilient packing member adapted to curve the signature.

11. In an assembling machine for aligning and stacking signatures provided with a margin to be bound, the combination including means for orienting the signatures to be stacked from a horizontal position into a vertical position with the margins to be bound on the bottom, a vibratory support, booster members for feeding the signatures longitudinally upon the vibratory support, means for actuating the signatures laterally on the vibratory support, and a chute aligned with the vibratory support for receiving the signatures advanced laterally from the vibratory support into the chute.

12. In an assembling machine for aligning and stacking signatures provided with a margin to be bound, the combination including means for orienting the signatures to be stacked from a horizontal position into a vertical position with the margins to be bound on the bottom, a vibratory support, booster members for feeding the signatures longitudinally upon the vibratory support, means for actuating the signatures laterally on the vibratory support, a chute aligned with the vibratory support for receiving the signatures advanced laterally from the vibratory support into the chute, and means for vibrating the chute to facilitate the lateral movement of the signatures in the chute.

13. In an assembling machine for aligning and stacking signatures provided with a margin to be bound, the combination including means for orienting the signatures to be stacked from a horizontal position into a vertical position with the margins to be bound on the bottom, a vibratory support terminating in a plurality of projections, means for vibrating the vibratory support, means for advancing the signatures longitudinally upon the vibratory support, a chute provided with cut-away areas complementing the projections of the vibratory support, and means for actuating the signatures laterally upon the vibratory support so as to cause the signatures to be actuated from the vibratory support into the chute.

14. In an assembling machine for aligning and stacking signatures provided with a margin to be bound, the combination including means for orienting the signatures to be stacked from a horizontal position into a vertical position with the margins to be bound on the bottom, a vibratory support terminating in a plurality of projections, means for vibrating the vibratory support, means for advancing the signatures longitudinally upon the vibratory support, a chute provided with cut-away areas complementing the projections of the vibratory support, means for actuating the signatures laterally upon the vibratory support so as to cause the signatures to be actuated from the vibratory support into the chute, and

means for vibrating the chute to facilitate the feeding of the signatures through the chute.

15. In an assembling machine for aligning and stacking signatures provided with a margin to be bound, the combination including means for orienting the signatures to be stacked from a horizontal position into a vertical position with the margins to be bound on the bottom, a vibratory support terminating in a plurality of projections, means for vibrating the vibratory support, means for advancing the signatures longitudinally upon the vibratory support, a chute provided with cut-away areas complementing the projections of the vibratory support, means for actuating the signatures laterally upon the vibratory support so as to cause the signatures to be actuated from the vibratory support into the chute, and means tending to separate the signatures upon the vibratory support to facilitate alignment of the margins to be bound into a common plane.

16. In an assembling machine for aligning and stacking signatures provided with a margin to be bound, the combination including means for orienting the signatures to be stacked from a horizontal position into a vertical position with the margins to be bound on the bottom, a vibratory support terminating in a plurality of projections, means for vibrating the vibratory support, means for advancing the signatures longitudinally upon the vibratory support, a chute provided with cut-away areas complementing the projections of the vibratory support, means for actuating the signatures laterally upon the vibratory support so as to cause the signatures to be actuated from the vibratory support into the chute, means tending to separate the signatures upon the vibratory support to facilitate alignment of the margins to be bound into a common plane, and means for vibrating the chute to facilitate the feeding of the signatures from the vibratory support into the chute.

17. In an assembling machine for aligning and stacking signatures provided with a margin to be bound, the combination including means for orienting the signatures to be stacked from a horizontal position into a vertical position with the margins to be bound on the bottom, a vibratory support terminating in a plurality of projections, means for vibrating the vibratory support, means for advancing the signatures longitudinally upon the vibratory support, a chute provided with cut-away areas complementing the projections of the vibratory support, means for actuating the signatures laterally upon the vibratory support so as to cause the signatures to be actuated from the vibratory support into the chute, means tending to separate the signatures upon the vibratory support to facilitate alignment of the margins to be bound into a common plane, means for vibrating the chute to facilitate the feeding of the signatures from the vibratory support into the chute, and a magazine aligned with the chute, said magazine having an open end facing the chute so that the signatures may be fed from the chute into the magazine.

18. In a packing mechanism for packing signatures

into a chute, comprising a vibratory support, means for feeding the signatures onto said support, an actuator provided with a reciprocatory member pivotally mounted on an eccentric and slidably mounted at one end thereof, a resilient packing member attached to a cam follower, said resilient member being adapted to be reciprocated by said reciprocatory member, said cam follower having a larger stroke than the reciprocatory member so that the center of the resilient member travels through a larger stroke than its end so as to curve the signatures, a chute adapted to receive said curved signatures provided with sides spaced apart at a distance less than the overall length of the signatures, rollers in said chute to facilitate movement of said signatures to the bottom of said chute.

19. In a packing assembly for packing signatures into a chute comprising a vibratory support, means for feeding the signatures onto said support, an actuator assembly having a member pivotally mounted on an eccentric and slidably mounted at one end thereof, a resilient packing member attached to a cam follower at its center and retained at its ends by leaf springs attached to said member, said resilient member being reciprocated transverse of the vibratory support so as to curve the signatures, a chute adapted to receive said signatures provided with sides which are spaced apart a distance less than the overall length of the signatures.

20. In a packing mechanism for packing signatures into a chute, comprising a vibratory support, means for feeding the signatures onto said support, an actuator provided with a reciprocatory member pivotally mounted on an eccentric and slidably mounted at one end thereof, a resilient packing member attached to a cam follower, said resilient member being adapted to be reciprocated by said reciprocatory member, said cam follower having a larger stroke than the reciprocatory member so that the center of the resilient member travels through a larger stroke than its end so as to curve the signatures, said resilient member forcing the signatures into a chute provided with sides spaced apart a distance less than the overall length of the signatures.
